UNITED STATES PATENT OFFICE

109,540

DESIGN FOR A HIGHWAY TRAFFIC SIGNAL

George E. Archer, South Whitley, Ind.

Application February 16, 1938, Serial No. 75,193

Term of patent 14 years

To all whom it may concern:

Be it known that I, George E. Archer, a citizen of the United States, residing at South Whitley, in the county of Whitley and State of Indiana, have invented a new, original, and ornamental Design for Highway Traffic Signals, of which the following is a specification, reference being had to the accompanying drawing, forming part thereof.

Fig. 1 is a front perspective view of a highway traffic signal showing my new design.

Fig. 2 is a rear perspective view of the same, a part of the base being omitted.

I claim:

The ornamental design for a highway traffic signal, as shown.

GEORGE E. ARCHER.
